ELECTRIC LAMP SOCKET

Arvid H. Nero, West Hartford, Conn., assignor to
 The Arrow-Hart & Hegeman Electric Company,
 Hartford, Conn., a corporation of Connecticut

Application May 24, 1929, Serial No. 365,683

5 Claims. (Cl. 173—354)

This invention relates to electric lamp sockets and more particularly to those types of electric lamp sockets which are used in electric candle fixtures and which often have an electric switch 5 structurally combined therewith.

It is an object of my invention to simplify the construction of the above type of lamp sockets to decrease their cost of manufacture and the time required to assemble and install them.

10 Another object of my invention is to provide an improved supporting means for electric lamp sockets of the above types.

Other objects will be apparent as my invention is described in connection with the accompanying drawing in which

Fig. 1 is a broken front elevation section view of my lamp socket invention with the section taken upon line 1—1 of Fig. 4.

Fig. 2 is a broken side elevation section view 20 of my invention taken upon line 2—2 of Fig. 4.

Fig. 3 is a broken front elevation of my lamp socket invention.

Fig. 4 is a top plan view of my lamp socket invention.

25 Fig. 5 is a detail view of the single member used to space the insulating plates and secure the lamp socket above them.

Fig. 6 is a detail view of the insulating disc which I locate within the screw shell in practicing my invention.

Fig. 7 is a fragmentary detail view of a lower corner of one of the insulating plates showing the binding terminal construction which I use in practicing my invention.

30 Fig. 8 is a section view of the hickey used in my invention, the section being taken on line 8—8 of Fig. 2.

Referring to the drawing it will be noted that a conventional screw shell contact 10 is placed 40 upon the short edges of two parallel, rectangular, spaced, insulating plates 12, 14. These plates are located in planes substantially perpendicular to the bottom of the screw shell and are assembled in that position by means as 45 hereinafter described.

For the purpose of insulating a center lamp contact 20 from the bottom of the screw shell I place in the bottom of the screw shell an elongated, slotted insulating disc 15 with rounded 50 ends. The center lamp contact 20 is made of a strip of metal having ears 21, 22 laterally projecting from its middle portion and bent at right angles so as to extend through apertures in the insulating plate 12, the ends of the ears then 55 being bent over on the plate 12 to hold the

center contact to the plate. The top of the center lamp contact projects through an aperture 13 in the bottom of the screw without engaging the shell and it then extends through a slot 16 in the insulating disc 15, and is bent over so it 60 may be engaged by the center contact of an electric lamp when an electric lamp is screwed in the shell.

To hold the insulating disc 15 in the shell and at the same time to space the insulating plates 65 12, 14 and secure them to the shell 10, I place a securing ring 30 within the shell and upon the disc 15. This ring has diametrically opposed extensions 32, 34 of equal width. These extensions are bent down at right angles to the plane 70 of the ring, and extend through slots 37, 39, in the bottom of the screw shell and between the plates 12, 14. Projecting laterally from the extensions 32, 34 are fingers 33, 35 which protrude through small apertures in the upper portion of 75 the plates 12, 14. The ends of these fingers are deformed or spread in order to secure the plates in spaced parallel relation to each other and to hold them beneath and perpendicular to the bottom of the screw shell.

80 To securely hold the disc 15 to the bottom of the screw shell diametrically opposed and downwardly bent lugs 36, 38 are formed upon the periphery of the securing ring 30. These lugs are angularly spaced approximately 90° from the 85 extensions 32, 34 of the ring. The lugs project through small slots in the bottom of the screw shell and their ends are bent over thus clamping the screw shell 10, insulating disc 15, and ring 30 securely together.

90 It will be noted that I make the extension 34 longer than the extension 32 and I provide it with a binding screw. This extension 34, while acting to hold the plates 12, 14 in spaced relation also acts as a binding terminal for the 95 screw shell.

To support the above described socket mechanism I provide a two piece adjustable hickey having upper and lower members 40, 42 slidably engaging each other. The upper member 100 consists of a straight strip of metal having a series of right angle bends in it giving the upper end of the member 40 a hooked formation. The top horizontal portion of the member 40 has laterally extending fingers 44 which project through 105 small apertures in the lower ends of the plates 12, 14 and have their ends spread to secure the plates and hickey together.

The lower member 42 of the hickey also is 110 formed of a strip of metal and has a right angle

bend at its lower end producing a horizontal portion 42' which is apertured and contains an internally threaded boss 45 by means of which the socket may be screwed to a fixture in the 5 usual manner.

The vertical portions 41, 43 of the hickey members 40, 42 are laterally curved (see Fig. 8) as by depressing each of the members along its longitudinal axis while maintaining its longitudinal edges in their original plane.

In order that the height of the screw shell above the boss 45 may be changed to suit the varying conditions of use a long centrally located longitudinal slot 46 is provided in the 15 lower member 42. Through this slot a securing screw 47 passes to a threaded aperture located at the lower end of the upper member 40. To guide the sliding of the upper member on the lower member, a hole 48 is punched through the 20 middle of the upper member a short distance from the screw aperture and the periphery of the hole is extruded so that the edges of the longitudinal slot 46 rub against this extruded periphery 49 and are guided thereby when the 25 hickey is extended or retracted.

To control the current through the socket I place a switch mechanism between the plates 12, 14. This switch mechanism forms no part of this invention and will therefore only be 30 described briefly to show its cooperation in the present combination.

The switch spindle 50 which is journaled transversely through the center of the plates 12, 14 carries a movable switch contact 52 which 35 bridges two stationary switch contacts 54, 56. The stationary switch contact 54 is formed integral with and extends laterally from the lower end of the center lamp contact 20. This switch contact 54 extends into and across one of four 40 curved concentric apertures 57, 58, 59, 60 which are spaced equal distances from and about the spindle hole in the plate 12.

The stationary switch contact 56, extends across and down into another of the segmental slots, i. e. 60, which is diametrically opposite to the segmental slot 58 in which the stationary switch contact 54 is.

This switch contact 56 is formed integrally with a binding terminal plate 62 located under 50 a lower corner of the plate 12. Ears 68 project perpendicularly from the plate 62 and are bent over the plate 12 to hold the plate 12 and terminal plate 62 together. A portion of the corner of the plate 12 is cut away over the plate 62 to form a pocket 65 for the head of a binding screw 64. This is a very desirable construction because the rounded edge of the pocket 65 will hold a lead wire led around the shank of the binding screw 64 from slipping out from 60 under the screw head when the screw is being screwed down to secure the lead wire to the terminal plate. The bridging contact is actuated by a chain 70 through mechanism substantially as described in the copending application 65 of Harry T. Paiste, Serial No. 315,532. Since this switch mechanism forms no part of this invention it need not be further described herein.

When the switch is in circuit making position,

70

the current from the source of power may enter the device through the terminal plate 62, pass through the switch contacts 56, 52, 54 to the center lamp contact 20, then pass through the lamp which may be screwed in the socket, then to the screw shell 10 and securing ring 30 and the binding terminal 34, back to the source of power.

Many modifications within the scope of my invention will occur to those skilled in the art, and therefore I do not limit myself to the specific embodiment shown, but,

I claim:

1. An electric lamp socket comprising a screw shell, a plurality of substantially parallel spaced insulating plates, a slotted insulating disc within said shell and a single means spacing said plates apart, securing said disc in said shell, and mounting said shell over said plates, in combination with a center contact secured to one of said plates and projecting through a slot in said disc.

2. In an electric lamp socket and switch device, mutually insulated screw shell and center lamp contacts, a slotted insulating disc within said shell, a plurality of substantially parallel spaced insulating plates assembled beneath said shell and a single member securing said disc in said shell, spacing said plates apart beneath said shell, and holding all the aforementioned parts in assembled position, in combination with switch mechanism located between said plates, said switch mechanism comprising fixed and movable contacts, one of said fixed contacts being formed integrally with said center lamp contact.

3. In an electric lamp socket and switch device, mutually insulated screw shell and center lamp contacts, a slotted insulating disc within said shell, a plurality of substantially parallel spaced insulating plates assembled beneath said shell and a single member securing said disc in said shell, spacing said plates apart beneath said shell, and holding all the aforementioned parts in assembled position, in combination with switch mechanism located between said plates, said switch mechanism comprising fixed and movable contacts, one of said fixed contacts being formed integrally with said center lamp contact, another of said fixed contacts being formed integrally with a binding terminal.

4. An electric lamp socket comprising mutually insulated screw shell and center contacts, a plurality of spaced insulating plates, an insulating disc within said shell, a single means spacing said plates apart beneath said shell and securing said disc within said shell, and a binding terminal formed integrally with said single means.

5. An electric lamp socket comprising mutually insulated screw shell and center contacts, a pair of substantially parallel insulating plates assembled beneath said shell in planes substantially perpendicular to the bottom of said shell, a single member holding said plates and said shell in assembled position, and a binding terminal formed integrally with said single means.

ARVID H. NERO.
